LEVER FOR USE AS A WALKING BEAM OR
THE LIKE

Walter H. Scales, New Orleans, La., assignor, by
mesne assignments, to Timber Engineering
Company, Washington, D. C., a corporation of
Delaware

Application June 13, 1938, Serial No. 213,483

1 Claim. (Cl. 74—519)

The invention relates to levers and has as an object the provision of a lever constructed to withstand the strains of use as a walking beam, as for instance to operate an oil well pump.

5 It is a further object of the invention to provide a lever so fashioned that it can be thoroughly creosoted against decay.

It is a further object of the invention to provide a lever that will have slight tendency to 10 checking and warping.

It is a further object of the invention to provide a lever that may be made of timbers of relatively small dimensions.

15 It is a further object of the invention to provide a lever that can be assembled at the place of use to avoid the inconvenience of shipping the same in a single piece.

20 Further objects of the invention will appear from the following description when read in connection with the accompanying drawings showing 25 illustrative embodiments of the invention, and wherein:—

Figure 1 is a plan view of one form of the invention;

25 Fig. 2 is a side view of the same;

Fig. 3 is an end view seen from the right of Figures 1 and 2 and drawn to an enlarged scale;

Fig. 4 is a vertical transverse section on line 4—4 of Figure 2;

30 Figs. 5 to 7 inclusive are views corresponding to Figures 1 to 3 inclusive of another form of the invention;

Fig. 8 is a vertical transverse section on line 8—8 of Figure 6;

35 Figs. 9, 10, and 11 are views corresponding to Figures 1 to 3 inclusive of a still further form of the invention; and

Fig. 12 is a vertical transverse section on line 12—12 of Figure 10.

40 Levers to serve as walking beams to operate pumps in oil wells must be of enormous strength. A usual size when made of timber is 14 x 26 inches in cross section by 26 feet long, and they should have a safe working load capacity of approximately twelve tons for operation of a one and one-half inch pump in a well of 4500 feet depth. It has been customary to construct levers of this character of a single timber which is obviously cumbersome to ship.

45 It is impossible also to creosote a timber of the dimensions referred to in such a manner as to cause the creosote to strike entirely through the same, and furthermore particularly when subjected to the hot sun and dry climate of the oil fields the single timber lever will split and warp

5 in such a manner as to weaken the same. The total result is that the structures now in use are relatively short-lived and quite expensive to renew.

In accordance with the present invention the 5 lever is built up of parts and to cause the parts to work together as a unit, they are bolted together with timber connectors inserted therebetween in a particular manner of placement.

The result is that the smaller timbers utilized 10 may be more effectually creosoted and the moisture content reduced to the point desired. By virtue of the structure shown any warping or splitting due to climatic effect will not extend through a sufficient portion of the assembled 15 lever as to materially weaken it.

In the form of Figures 1 to 4 inclusive of the drawings, the individual parts 15 of the beam are constituted of timbers on edge. Desirable dimensions for these timbers is a thickness of three 20 inches and any width readily available preferably assembled with the joints staggered.

Desirably as shown in this form of the invention the timber is given a quasi T-form by reason of the fact that the outer timbers 15' do not extend the full depth of the lever. To hold the portions 15 and 15' in assembly there are shown through-bolts 16, timber connectors 17 being placed around each bolt at each contact of the faces of the timbers. The added timbers 15' at 30 the upper surface of the lever will assist in resisting the tension upon the lever which is of course greatest at its upper surface. The greatest tendency to slippage of the timbers upon each other will be toward the ends of the lever, and as shown at these portions the bolts 16 and the accompanying connectors 17 are more closely spaced than adjacent the center of the lever. Any type of timber connector may be used in the lever of 35 the invention.

In Figures 5 to 8 inclusive the individual members 18 making up the lever are placed flatwise. This form is slightly less resistant to the stresses than the form of Figures 1 to 4 inclusive but is more readily constructed since it is not difficult 45 to secure the individual timbers of dimensions up to 14 inches in width, when the lever is to be of the dimensions of 14 by 26 inches as above indicated. In this form of the invention, there is illustrated the use of connectors 19 commonly known as Smitt grid connectors but of a special form whereby each coacts with both of a pair of through-bolts 20. In this form of the invention also the connectors are more closely spaced 50 adjacent the ends of the lever.

Certain of the timbers at the lower portion of the lever are shown as progressively shorter as at 21, 22, and 23 to provide the extra strength required at the center of the lever where the 5 fulcrum will be applied.

In the form of Figures 9 to 12 inclusive the lever is made up of a combination of units on edge and placed flatwise with connectors 24 placed about all of the through-bolts 25, 26.

10 The timbers 27 placed on edge are provided with the through-bolts 25 and the timbers 28, 29 placed flatwise are connected to the assembled timbers 27 by the throughbolts 26. Certain of the timbers 28 and 29 are shown as applied to the 15 central portion of the lever for the required added strength therein. In this form of the invention also the connectors are more closely spaced at the ends of the lever than at its central portion.

The individual portions which make up the 20 lever of the invention may be framed, bored and prepared for insertion of the timber connectors at the mill and may then be readily shipped in the manner of common lumber to the place of use where they may be assembled with the required 25 hoisting means for placing readily at hand.

Minor changes may be made in the physical embodiments of the invention within the scope of the appended claim without departing from the spirit thereof.

I claim:

5 A timber lever of the walking beam type comprising, in combination: a plurality of laminations of substantial thickness formed of elements integral throughout the length of the lever; said laminations lying face to face in parallel planes; 10 said laminations comprising elements placed in meeting edge to edge relation in the lamination; the joints between said meeting edges being in staggered relation to the joints of the adjacent lamination; a plurality of bolts passing through 15 said laminations, securing each of the individual elements to an element of an adjacent lamination; the connecting bolts adjacent the ends of the lever more closely spaced than those near the middle thereof; and timber connectors sunk into 20 the meeting faces of the laminations around at least some of said bolts; whereby said elements may be individually creosoted, framed and shipped in disassembled relation.

WALTER H. SCALES.
